L. V. LEWIS

RAILWAY TRAFFIC CONTROLLING APPARATUS

Original Filed Nov. 25, 1918

Patented June 12, 1923.

1,458,183

UNITED STATES PATENT OFFICE.

LLOYD V. LEWIS, OF EDGEWOOD BOROUGH, PENNSYLVANIA, ASSIGNOR TO THE UNION SWITCHE & SIGNAL COMPANY, OF SWISSVALE, PENNSYLVANIA, A CORPORATION OF PENNSYLVANIA.

RAILWAY-TRAFFIC-CONTROLLING APPARATUS.

Original application filed November 25, 1918, Serial No. 263,969. Patent No. 1,377,137, dated May 3, 1921. Divided and this application filed March 24, 1921. Serial No. 455,140.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Apparatus, of which the following is a specification.

My invention relates to railway traffic controlling apparatus, and has for an object the provision of simple and reliable means for transmitting to a railway vehicle indications of traffic conditions in advance without mechanical or electrical contact between devices on the vehicle and devices in the trackway.

The present application is a division of my copending application filed November 25, 1918, Serial No. 263,969, for railway traffic controlling apparatus, which application has matured into Patent No. 1,377,137, dated May 3, 1921.

I will describe one form of apparatus embodying my invention, and will then point out the novel features thereof in claims.

The accompanying drawing is a diagrammatic view showing one form of railway traffic controlling apparatus embodying my invention.

Referring to the drawing, the reference characters H and H' designate the track rails of a railway, which rails are divided into block sections $A-B$, $B-C$, etc., by insulated joints 2. Each section is provided with a track circuit comprising the two track rails of the section, a track battery 3, and a track relay designated by the reference character F with an exponent corresponding to the location of the relay. These track relays are employed to control the indications transmitted to the vehicles traveling along the railway, in a manner hereinafter explained.

Located in block section $A-B$ is a vehicle V (railway car or train) which is represented by two axles and two pairs of wheels. This vehicle is provided with apparatus which I will now describe.

Mounted on the vehicle is an electron tube K comprising a vacuum bulb 4, containing a filament 5, a plate 6, and a grid 7 between the filament and the plate. The filament 5 is constantly heated to incandescence by a battery 8 through a circuit which is obvious

from the drawing. Between the grid 7 and filament 5 an alternating difference of potential is maintained due to sustained oscillations in a circuit a which is tuned to resonance at a predetermined frequency, and the oscillations in this circuit a are in turn maintained by a portion of the energy output from the plate circuit of the electron tube K . The grid circuit a passes from the secondary 12 of a transformer T^3 , through condenser 11, wire 70, coil 23 wound on a core 24, and wire 69 to the secondary 12 of transformer T^3 . The terminals of condenser 11 are connected with the filament and grid respectively of the electron tube K , a blocking condenser 9 being included in the connection as shown. A high resistance or "grid leak" 10 is optionally connected in multiple with the condenser 9 in order to prevent the accumulation of an excessive negative charge on the grid 7. The plate circuit for tube K passes from battery 13 through wires 14 and 71, contact 72 of a relay R , wire 73, primary of transformer T^2 , wire 74, primary 19 of transformer T^3 , wire 20, thence through tube K to battery 13. The tube K and associated circuits, therefore, constitute a self-excited generator of alternating current of a frequency determined by the constants of circuit a .

The coil 23 in circuit a is wound on a core 24 of magnetizable material such as laminated soft iron. This core is U-shaped as shown, with its legs projecting downwardly, and the plane of the core is parallel to the track rails H and H' . Located at certain points in the trackway are bars D of soft iron, preferably laminated, each of which bars is also parallel with the track rails, and is so positioned that it is directly under and close to the open ends of core 24 as the vehicle passes over the bar.

The plate circuit of tube K will, of course, deliver pulsating current of a frequency which depends on the constants of circuit a , and so this frequency will be of one value when core 24 is not influenced by a bar D , and a different value when the core is over a trackway bar, due to the change in the reluctance of the magnetic circuit of core 24 when it is in proximity to bar D . The first of these values will hereinafter be termed the "given" frequency.

The letter *b* designates another circuit which is loosely coupled to the plate circuit of tube K by the transformer T². Circuit *b* is from the secondary of transformer T² 5 through wire 75, condenser 46, wires 62 and 70, coil 44, and wire 68 to the secondary of transformer T². The elements in this circuit are so proportioned that the circuit is resonant to current of the given frequency, 10 that is, the frequency delivered by tube K when circuit *a* is not influenced by a bar D. Circuit *b* constitutes the grid circuit for a second electron tube K', and to this end the terminals of condenser 46 are connected with the filament and grid respectively of such tube, a blocking condenser 47 being inserted in this connection as shown.

The plate circuit for tube K' controls 20 relay R, this circuit being from battery 13 through wire 14, relay winding 66, relay winding 64 and condenser 65 in multiple, wire 63, then through tube K' and wire 62 to battery 13. Since relay R is of the well known induction motor type, it is not affected by the continuous or steady component of the current in this circuit, but by reason of the condenser 65 connected across winding 64 the alternating components of 25 the currents in the relay windings are displaced in phase to produce a rotating field to cause the rotor to close contacts 50 and 72. Furthermore, when current of the given frequency is supplied to circuit *b*, by electron tube K, the amplitude of the current variations in relay R is sufficient to cause this relay to close, but when any other frequency is supplied to circuit *b* due to the influence of a trackway bar D, upon the 30 circuit *a* which controls the frequency delivered by electron tube K, the amplitude of the current variations in relay R is materially reduced due to the fact that circuit *b* is not resonant to such frequency, and 35 relay R will then open unless supplied with current from another source as hereinafter explained.

Relay R controls a brake application magnet M, the circuit being from battery 27, 40 through the winding of magnet M, and contact 50 of relay R to battery 27. The magnet M controls brake application apparatus of any suitable form, in such manner that an automatic application of the brakes 45 occurs whenever this magnet becomes de-energized.

The coil 44 in circuit *b* is wound on a core 45 of magnetizable material such as laminated soft iron. This core is U-shaped, 50 with its legs projecting downwardly, and is arranged transversely with respect to the track, as shown in the drawing. Located in the trackway adjacent each bar D is a conductor W, which is at times supplied 55 with alternating current by means herein-

after explained. When the vehicle-carried core 45 passes over a conductor W in which alternating current of the given frequency is flowing, part of the magnetic lines of force surrounding the conductor pass 70 through the core 45 and so induce an alternating potential in the coil 44, whereupon sustained oscillations are produced in the resonant circuit *b*. This produces an alternating difference of potential across the 75 grid and filament of electron tube K' of sufficient intensity to cause relay R to close, regardless of the condition of circuit *a*.

Each block section is provided with one of the bars D, which bar is located at maximum braking distance in the rear of the entrance end of the section. Adjacent to each of the bars D is one of the conductors W, this conductor preferably extending a short distance beyond each end of the adjacent bar D. Each conductor is supplied at times with alternating current of the given frequency, this supply being controlled by the track relay for the corresponding section. For example, the ends 80 of the conductor W in the rear of point B are connected with the terminals of the secondary of a transformer E, and the circuit for the primary of this transformer is from the secondary of transformer J^B, through contact 52 of track relay F^B, wire 53, primary of transformer E, and wire 54 to the secondary of transformer J^B. Conductor W in the rear of location C is similarly supplied with current from a transformer J^C, this supply being controlled by track relay F^C. The primary of each transformer J is connected with a transmission line L, which line is constantly supplied 85 with alternating current from a suitable 90 source, such as a generator G.

The operation of the system is as follows:

The section immediately in advance of location C being occupied by a vehicle V', track relay F^C is de-energized; but inasmuch as a block section B-C is unoccupied, relay F^B is energized so that the conductor W controlled by this relay is supplied with 110 alternating current. Vehicle V is assumed to have just entered block section A-B. Relay R on this vehicle is, of course, energized, and brake magnet M is consequently energized, so that the vehicle is free to proceed into block section A-B. When the 120 vehicle reaches such a position that the core 24 passes over the trackway bar D, the current supplied to relay R due to oscillator K will be materially reduced, but this relay will remain energized due to conductor W. 125 Vehicle V can, consequently, proceed into block section B-C without interference on the part of the automatic apparatus.

Inasmuch as track relay F^C is de-energized, the conductor W in the rear of loca- 130

tion C is not supplied with current. It follows that when vehicle V reaches such point that its core 24 passes over the bar D in block section B—C, the consequent change in the inductance of circuit a will permit relay R to open, and that upon leaving the bar this relay will remain open, because the plate circuit for tube K will remain open at contact 72. The opening of relay R will de-energize magnet M so that an automatic application of the brakes will immediately occur, whereby the vehicle will be brought to a stop before it reaches location C.

In order to allow the vehicle to proceed after an automatic brake application has occurred, a push button 76 is provided which is normally open but which, when closed, closes a shunt around contact 72 of relay R and so closes the plate circuit for tube K even though relay R is de-energized. This push button is preferably located at such a place on the vehicle that it is accessible only from the ground, thus requiring the vehicle to come to rest before the button can be operated. Assuming, then, that the vehicle has been brought to rest by an automatic application of the brakes, the operator descends to the ground and pushes button 76, thus energizing relay R. This relay will then remain energized, and will cause magnet M to become energized, so that the brakes will again be released and the vehicle may proceed.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a vehicle, governing means thereon held in inactive condition when supplied with pulsating current of a given frequency, a source of pulsating current on said vehicle normally delivering current of said given frequency to said governing means, devices located at intervals in the trackway for varying the frequency of said source and thereby placing said vehicle governing means in active condition, and means located in the trackway and controlled by traffic conditions in advance for modifying the effect of said trackway devices on said governing means.

2. Railway traffic controlling apparatus comprising a vehicle, governing means thereon held in inactive condition when supplied with pulsating current of a given frequency, a source of pulsating current on said vehicle normally delivering current of said given frequency to said governing means, devices located at intervals in the trackway

for varying the frequency of said source and thereby placing said vehicle governing means in active condition, and other devices located at intervals in the trackway for supplying current of said given frequency to said governing means and thereby nullifying the effect thereon of said first-mentioned trackway devices.

3. Railway traffic controlling apparatus comprising a vehicle, a circuit thereon containing inductance and capacity, a source of pulsating current on the vehicle the frequency of which depends upon the value of the inductance in said circuit, governing means on the vehicle controlled by current from said source and held in inactive condition when said current is of a given frequency, devices located in the trackway for varying the inductance in said circuit and thereby varying the frequency supplied to said governing means to place the latter in active condition, and other devices located in the trackway for supplying current of said given frequency to said governing means.

4. Railway traffic controlling apparatus comprising a vehicle, a circuit thereon containing inductance and capacity, an electron tube oscillator for energizing said circuit and delivering pulsating current of a frequency determined by the natural period of said circuit, governing means on the vehicle controlled by current from said oscillator and held in inactive condition when said current is of a predetermined given frequency, devices located in the trackway for varying said inductance and thereby changing the frequency of the current delivered by said oscillator to a degree sufficient to place said governing means in active condition, and other trackway devices for nullifying the effect of the first-mentioned devices on said governing means.

5. Railway traffic controlling apparatus comprising a vehicle, a circuit thereon tuned to resonance at a given frequency, means on the vehicle for supplying current of said frequency to said circuit, vehicle governing means controlled by said circuit and held in inactive condition when current of said frequency is supplied to said circuit, devices located at intervals in the trackway for temporarily changing the frequency of the current supplied to said circuit, and other devices located in the trackway adjacent said first-mentioned devices and controlled by traffic conditions in advance for supplying current of said given frequency to said circuit.

6. Railway traffic controlling apparatus comprising a vehicle; an electron tube thereon having an incandescent filament, a plate, and a grid interposed between the two; a plate circuit for said electron tube including a source of current and the primary of

4
 a transformer, a grid circuit for said electron tube including a condenser, a circuit *a* including said condenser and the secondary of said transformer and said circuit *a* being tuned to resonance at a given frequency whereby current of said frequency is maintained in the plate circuit, a circuit *b* tuned to resonance at the same frequency as circuit *a* and arranged to be energized inductively from said plate circuit, vehicle governing means on the vehicle controlled by circuit *b* and held in inactive condition when current of said given frequency is supplied to circuit *b*, devices located at intervals in the trackway for changing the tuning of circuit *a* so that current of a different frequency is supplied to circuit *b*, and other devices located in the trackway adjacent said first-mentioned devices and controlled by traffic conditions in advance for supplying current of said first-mentioned frequency to circuit *b*.

7. Railway traffic controlling apparatus comprising a vehicle; an electron tube thereon having an incandescent filament, a plate and grid interposed between the two; a plate circuit for said electron tube including a source of current and the primary of a transformer, a grid circuit for said electron tube including a condenser, a circuit *a* including said condenser and the secondary of said transformer and said circuit *a* being tuned to resonance at a given frequency whereby current of said frequency is maintained in the plate circuit, a circuit *b* tuned to resonance at the same frequency as circuit *a* and arranged to be energized inductively from said plate circuit, a relay con-

trolled by said circuit *b* and arranged to be effectively energized only when current of said given frequency is supplied to circuit *b*, the plate circuit of said electron tube being controlled by said relay in such manner that the circuit is closed only when the relay is effectively energized, vehicle governing means controlled by said relay and held in inactive condition when the relay is effectively energized, devices located at intervals in the trackway for changing the tuning of circuit *a* so that current of a different frequency is supplied to circuit *b*, and other devices located in the trackway adjacent said first-mentioned devices and controlled by traffic conditions in advance for supplying current of said first-mentioned frequency to circuit *b*.

8. Railway traffic controlling apparatus comprising a vehicle, a circuit thereon tuned to resonance at a given frequency, means on the vehicle for supplying current of said frequency to said circuit, an electron tube having a grid circuit controlled by said first circuit, vehicle governing means controlled by the plate circuit of said electron tube and held in inactive condition when current of said given frequency is supplied to the first circuit, devices located at intervals in the trackway for temporarily changing the frequency of the current supplied to said first circuit, and other devices located in the trackway adjacent said first-mentioned devices and controlled by traffic conditions in advance for supplying current of said given frequency to said first circuit.

In testimony whereof I affix my signature.
 LLOYD V. LEWIS.
